UNITED STATES PATENT OFFICE.

AXEL G. GULBRANSEN, OF CHICAGO, ILLINOIS.

PNEUMATIC-ACTION MECHANISM.

No. 874,763.

Specification of Letters Patent.

Patented Dec. 24, 1907.

Application filed December 11, 1906. Serial No. 347,306.

To all whom it may concern:

Be it known that I, AXEL G. GULBRANSEN, citizen of the United States, residing at Chicago, in the county of Cook and State of Illinois, have invented a certain new and useful Improvement in Pneumatic-Action Mechanism, of which the following is a full, clear, concise, and exact description, reference being had to the accompanying drawings, forming a part of this specification.

My invention relates to pneumatic action mechanism, particularly to such mechanism adapted for use in mechanical musical instruments, such as pianos, for operating the striking mechanism, and its object is to provide improved construction and arrangement of primary valve mechanism.

In my co-pending application, Serial No. 331,230, filed August 20, 1906, I described unitary action mechanisms arranged in staggered rows, each connected with one of the abstract rods of the piano to cause actuation thereof upon certain conditions of pressure in the mechanism. With the primary valve mechanism there shown I find that I cannot always attain the desired amount of power to sufficiently actuate the valve button and the prime object of this present application is to increase the power, which I accomplish by means of lever mechanism arranged between the valve actuating diaphragm and the valve button. With this arrangement I am enabled to attain any desired power and, therefore, more efficient operation of the mechanism.

In the accompanying drawing and description my invention will be clearly set forth.

In this drawing Figure 1 is a side view of a pneumatic action; Fig. 2 is a top view thereof; Fig. 3 is a sectional view taken on plane 3—3 of Fig. 1; Fig. 4 is a top view, the part above plane 4—4 of Fig. 1 being removed; and Fig. 5 is a vertical sectional view taken on plane 5—5 of Fig. 2.

Each action mechanism has a main mounting block 1 from the lower side of which are suspended any number of bellows 2—3, and so on, arranged in a vertical tier as shown, the swinging members 4 of the bellows being all connected together through link mechanism 5, and one of the swinging members having a cushioned abutment or extension 6 for engagement with some member connecting with the hammer actuating mechanism of the instrument. In the mounting block are the upper and lower diaphragm chambers 7

and 8 separated by the diaphragm 9 whose edges are glued to the annular ledge 10 between the chambers. Secured to the top of the mounting block over the diaphragm 60 chamber is the valve block 11 having therein the valve chamber 12 communicating with the upper diaphragm chamber through the port or passageway 13. Over and about the valve chamber is secured the washer or plate 65 14 having the central opening 15 through which the valve chamber may connect with atmosphere. In the valve chamber is the valve button 16 mounted on the stem 17, which may be an ordinary wood screw as 70 shown. The valve in its normal or lower position rests on the ledge 17' to close the opening 13, and when the valve is raised against the plate 14 the opening 15 is closed.

The valve chamber communicates with 75 the upper bellows 2 through the passageway 18 and with the lower bellows through the passageway 19. A bar or rod 20 is hinged at its rear end to the ledge 21 by means of the hinge or leather strip 22, this bar extending 80 forwardly diametrically across the upper diaphragm chamber, its bifurcated end 22' engaging the guide pin 23 extending upwardly from the mounting block. At some intermediary point this bar is engaged by the 85 lower end of the valve stem 17, which stem, as before stated, may be a wood screw; and the end thereof may be screwed into the bar 20. The central part of the diaphragm is also secured to the bar through the medium 90 of a block 24 and thus any vertical movement of the diaphragm is communicated to the bar and to the valve button.

In the device in my co-pending application referred to, the valve and diaphragm are concentric, but with this arrangement I found that I could not always obtain the desired power and I therefore place the diaphragm and valve in eccentric arrangement, the connection of the valve stem with the bar being 95 between the hinged end of the bar and its point of connection with the diaphragm, and therefore the force of the diaphragm to raise the bar is multiplied and the valve actuated with sufficient force. I could, of course, connect the valve stem with the bar at any other point and could reduce instead of multiplying the power of the diaphragm, if it were desirable. The pin 23 playing in the bifurcated end of the bar always maintains this bar 100 in its proper plane of vertical movement. The valve may be flexibly connected with

the bar, but I prefer to have this connection rigid, avoiding thereby the necessity of guiding means for the valve, which is necessary where the valve is disconnected from the bar 5 or diaphragm.

The upper diaphragm chamber communicates through passageway 25 with the low pressure chamber 26, and the lower diaphragm chamber communicates through passageway 27 and tube 27' with passageway 28, which passageway 28 in practice is connected with an opening in the tracker-board. The lower diaphragm chamber also communicates with the low pressure chamber 10 through a restricted opening 29 in the disk 30 covering the end of the passageway 27.

The operation is as follows: The parts are normally in the position shown. When the music sheet opens the end of the passageway 20 28 air or atmospheric pressure rushes through the passageways 28 and 27 into the lower diaphragm chamber to throw the diaphragm upwardly, this upward movement of the diaphragm being communicated to the bar 20 25 and eventually to the valve 16 which is raised to its upper position. The valve chamber is thus disconnected from atmosphere and connected with the low pressure chamber through the passageway 25, and the bellows 30 are therefore placed in communication with the low pressure chamber by way of the passageways 18 and 19, the valve chamber, opening 13 and passageway 25 and immediately collapse, their combined force being 35 accumulated to act on the striking mechanism engaged by the abutments 6. When the end of the passageway 28 is again closed the pressure of the upper and lower diaphragm chambers again becomes that of the low 40 pressure chamber, this equalization being enabled by the equalizing opening 29. This lever arrangement between the diaphragm and the valve enables me to attain the desired power to operate the valve with a limited 45 initial diaphragm actuating power and the action of the actuating device is very strong and reliable. This lever arrangement also enables me to give the valve a vertical movement greater or less than the vertical movement 50 of the diaphragm, which is also sometimes desirable.

Each actuating mechanism is a unitary self-contained structure, the parts being very compactly arranged, the drawings showing the 55 actual size of each unit, and these units are arranged in horizontal and staggered rows, each unit being secured at its end to the rear wall of the low pressure chamber by screws 31, the abutments 6 when the units 60 are thus arranged being alined to register with the abstract rods of the instrument so that the connection between the abutments and the abstract rods may be direct. By withdrawing its screws 31 any unit may be 65 withdrawn from the instrument independ-

ently of and without interfering with the other units.

I do not wish to be limited to the exact arrangement shown, as changes may readily be made without departing from the scope 70 of my invention.

I claim as new and desire to secure by Letters Patent:

1. In pneumatic action mechanism for mechanically operated instruments, the combination of a mounting block, a bellows supported from the under side of the mounting block, said mounting block forming one member of said bellows, a valve block on said mounting block, a valve supported on 75 said valve block, a diaphragm mounted in the mounting block, a lever pivoted at one end to the mounting block and engaged by the diaphragm and by the valve, movements of the diaphragm being transmitted through 80 the lever to the valve.

2. In pneumatic action mechanism for automatically operated instruments, the combination of a mounting block, a bellows mounted below said block, said block forming one of the members of said bellows, a diaphragm mounted in said block, a valve block on the mounting block, a valve chamber in the valve block connected with the bellows, a valve in said valve chamber, a lever disposed 90 between the valve and diaphragm and pivoted at one end to the mounting block whereby movements of the diaphragm are transmitted through the lever to the valve, and guiding means for the lever.

3. In pneumatic action mechanism for automatically operated pianos, the combination of a mounting block, a diaphragm mounted in said block, a bellows supported below the block, a valve block on the mounting block, a valve chamber in said valve block having connection with the bellows, a lever pivoted at one end to the mounting block and extending between the diaphragm and valve, engagement of the diaphragm and 105 valve with the lever upon movement of the diaphragm being at different points, whereby the movements of the diaphragm are either multiplied or reduced before reaching the valve.

4. In pneumatic action mechanism for automatically operated pianos, the combination of a mounting block, a bellows supported from the mounting block, a diaphragm chamber in said block, a diaphragm 120 in said diaphragm chamber, a valve block on said mounting block, a valve chamber in said valve block having connection with the bellows, a valve in said valve chamber, a lever pivoted at one end to the mounting block and extending across the diaphragm 125 chamber between the diaphragm and valve, movement of the diaphragm causing engagement of the diaphragm and valve with the lever and thereby transmission of motion 130

from the diaphragm to the lever, the points of engagement of the valve and diaphragm with the lever being in different planes.

5. In pneumatic action mechanism for automatically operated instruments, the combination of a mounting block 1, a bellows 2 supported below the mounting block, a diaphragm chamber 8, a diaphragm 9, a valve block 11 having a valve chamber 12, a valve 10 in the chamber, a lever 20 having a bifurcated end 22, said lever being pivoted to the mounting block at one end and extending

between the diaphragm and valve, whereby movements of the diaphragm are transmitted through the lever to the valve, and a 15 guide post 23 engaging in the bifurcated end 22' of the lever for guiding said lever.

In witness whereof, I hereunto subscribe my name this 5th day of December A. D., 1906.

AXEL G. GULBRANSÉN.
